UNITED STATES PATENT OFFICE.

JOHN HAUENSTEIN, JR., OF NEW ULM, MINNESOTA.

CIGAR AND CIGARETTE HOLDER.

1,080,552.

Specification of Letters Patent.

Patented Dec. 9, 1913.

Application filed November 8, 1911. Serial No. 659,122.

To all whom it may concern:

Be it known that I, JOHN HAUENSTEIN, Jr., a citizen of the United States, residing at New Ulm, in the county of Brown and State of Minnesota, have invented a new and useful Improvement in Cigar and Cigarette Holders, of which the following is a specification.

This invention relates to a device for holding cigars and cigarettes and the object of the invention is to inclose the cigar or cigarette so as to protect the user and others from sparks and ashes, the device being especially adapted for use while riding in automobiles, trains or other fast traveling vehicles.

The invention consists in the novel features of construction, hereinafter fully described, pointed out in the claim and shown in the accompanying drawings, in which,

Figure 1 is a longitudinal section. Fig. 2 is a transverse section on the line 2—2 of Fig. 1. Fig. 3 is a transverse section upon the line 3—3 of Fig. 1.

In these drawings 1 represents the mouth piece of the usual construction and in connection with this mouth piece, I employ a tube 2, preferably of aluminum, which receives the mouth piece, but is closed at the outer end. In the end portion adjacent the mouth piece is fitted a short cylindrical sec-

tion 3, and between said sections and the first mentioned tube is a lining 4, of asbestos. In advance of said cylinder 3, the tube 2 is provided with a series of reticulated portions 35 5, which may be in the form of rectangular openings having screens, as shown or said portions may be formed by perforating the tube.

What I claim is:

A cigar or cigarette holder comprising a mouth piece having a reduced and shouldered forward end, said mouth piece being adapted to receive and hold the cigar or cigarette to be smoked, and a metallic tube 45 closed at its forward end, the rear end of said tube being adapted to fit upon the reduced and shouldered end of the mouth piece, a packing of asbestos arranged within the rear end of the tube and a metallic 50 sleeve or lining arranged within said rear end and adapted to hold the asbestos packing in place, that portion of the tube in advance of the packing and lining being provided with a series of reticulated portions 55 arranged and adapted to operate, substantially as described.

JOHN HAUENSTEIN, Jr.
